[57] CLAIM

The ornamental design for surgical scalpel handle, as shown and described.

DESCRIPTION

FIG. 1 is a perspective view of a surgical scalpel handle, showing my new design;

FIG. 2 is an enlarged top plan view thereof;

FIG. 3 is a side elevational view thereof;

FIG. 4 is a bottom plan view thereof;

FIG. 5 is a side elevational view thereof, opposite that shown in FIG. 3;

FIG. 6 is a left end elevational view from FIG. 3;

FIG. 7 is a right end elevational view thereof from FIG. 3;

FIG. 8 is a side elevational view of a second embodiment of the surgical scalpel handle; and,

FIG. 9 is a side elevational view of the embodiment of the surgical scalpel handle illustrated in FIG. 8 taken from the opposite side of the handle the top, bottom and end views of the embodiment hereof illustrated in FIGS. 8-9 being identical to the top, bottom and end views of FIGS. 2, 4, 6 and 7, respectively.

The broken line showing of the blade in FIGS. 1-5, 8-9 is for illustrative purposes only and forms no part of the claimed design.
